[57] **CLAIM**

The design for a capped assembly of hair rollers, as shown.

DESCRIPTION

FIG. 1 is a perspective view of one roller component of my design for a capped assembly of rollers, shown separately from the assembly for clarity of illustration;

FIG. 2 is a top plan view shown on an enlarged scale;

FIG. 3 is a bottom plan view thereof;

FIG. 4 is an exploded perspective view of the assembly shown on a reduced scale, the partially disclosed inner rollers being similar to the outer roller disclosed except for their relative sizes; and,

FIG. 5 is a perspective view of the assembly fully assembled with the cap in place.
